NIGHT VIEWING DEVICE

Donald T. Heckel, San Jose, William R. Hill, Campbell,
and Robert H. Pfeiffer, Ben Lomond, Calif., assignors
to GTE Sylvania Incorporated

Filed Apr. 22, 1971, Ser. No. 136,630

Term of patent 3½ years

Int. Cl. D16—06

U.S. Cl. D57—1 E

FIG. 1 is a perspective view of a night viewing device showing our new design;

FIG. 2 is a side elevation thereof;

FIG. 3 is a top plan view thereof taken on line 3—3 of FIG. 2;

FIG. 4 is a front end view thereof taken on line 4—4 of FIG. 2;

FIG. 5 is a rear end view thereof taken on line 5—5 of FIG. 2.

We claim:

The ornamental design for a night viewing device, as shown and described.
